UNITED STATES PATENT OFFICE.

FRANK HAMACHEK, OF KEWAUNEE, WISCONSIN, ASSIGNOR TO FRANK HAMACHEK MACHINE COMPANY, OF KEWAUNEE, WISCONSIN, A CORPORATION OF WISCONSIN.

SEPARATING APRON FOR VINERS.

Application filed April 26, 1920. Serial No. 376,797.

To all whom it may concern:

Be it known that I, FRANK HAMACHEK, a citizen of the United States, and resident of Kewaunee, in the county of Kewaunee, and State of Wisconsin, have invented new and useful Improvements in Separating Aprons for Viners, of which the following is a description, reference being had to the accompanying drawings, which are a part 10 of this specification.

This invention relates to separating aprons for viners or pea vine threshing machines and the like and has for its object to prevent the loss of peas with the chaff 15 and to prevent injury of the peas.

One purpose of the invention is to provide the separating apron with a raised ridge at each edge that will prevent peas from rolling off of the apron.

Another purpose of the invention is to provide inclined guard-boards overhanging the edges of the inclined apron, said guard-boards being arranged with their edges diverging so as to spread the chaff 20 and peas over the apron and avoid depositing them in single lines thereon.

Another purpose of the invention is to provide for the discharge of matter that may find its way beneath the apron and 25 prevent it from falling upon the return bight of the apron.

Another purpose of the invention is to provide a discharge conveyer for conducting the chaff away from the apron, with 30 means for scraping the dirt from the apron and preventing the dirt and chaff from falling on the conveyer chains.

With the above and other objects in view the invention consists in the separating 35 apron for viners as herein claimed and all equivalents.

Referring to the accompanying drawings in which like characters of reference indicate the same parts in different views:

Fig. 1 is a transverse sectional view of 45 a viner, showing in longitudinal section the separating apron constructed in accordance with this invention;

Fig. 2 is a plan view of the separating 50 apron;

Fig. 3 is a transverse sectional view of one edge of the separating apron and the parts associated therewith;

Fig. 4 is an enlarged sectional view of 55 one edge of the separating apron, showing

the construction of the flexible bead or ridge formed thereon.

In these drawings, 10 indicates a screen drum rotatably mounted in a frame 11 on rollers 12, as usual, and containing rotatable beaters 13 for threshing pea vines or the like. The loose peas threshed from the vines, together with a quantity of chaff and dirt, fall through the screens of the screen drum 10 upon an inclined upwardly traveling endless separating apron 14 which carries the dirt and chaff upwardly, away from the loose peas which roll downwardly thereon into collecting boxes, not shown.

To facilitate the separation of the peas 70 from the chaff and dirt the apron is given an irregular movement by passing it around rollers 15 and 16 which are angular in cross section and one of which is suitably driven.

In order to keep the apron spread and 75 prevent it from creeping and bunching it is provided at intervals with cross-slats 17 extending from one edge to the other on its under face and these slats, as well as the edge of the apron, bear on run-boards 80 18 secured to the side frames 19, which are suitably fastened to the frame 11. As seen in Fig. 3, the run-boards 18 are secured to the side frames 19 by means of brackets 20, which are of triangular shape 85 and have secured to their lower faces inclined drain-boards 21 to prevent dirt falling from the run-boards 18 upon the lower bight of the separating apron. Such material is conducted by the drain-boards 90 21 beyond the edge of the separating apron, where it is discharged through a slot between the drain-boards and the side frames 19.

In order to provide a platform on which 95 a man may stand while removing the screen frames on the screen drum and which during the operation of the machine will support the apron and prevent it from sagging in the center, a platform 22 is positioned just beneath the upper bight of the separating apron.

This platform is made with 100 stringers 23 which are suitably secured to cross-rods or metal pipes 24 connecting the side frames 19 and while the edges of this 105 platform rest on the brackets 20, as shown in Fig. 3, they are spaced from the run-boards 18 to provide slots 25 between them to permit material to fall off of the run-boards upon the drain-boards, as described. 110

While working on the screen drum a person may stand on the platform without injury to the separator apron.

It is usual to provide inclined guard-
6 boards above the edges of the separating
apron to prevent the peas and other material
falling beyond the edges of the apron, but
as the edges of the guard-boards were in
line with the travel of the apron the mate-
10 rial falling therefrom was deposited to a
considerable depth in a narrow line and peas
embedded in the material were carried along
therewith over the upper end of the sepa-
rating apron and were so lost in the chaff.
15 This was particularly true at the feeding
end of the machine where large quantities of
dirt and loose leaves were dropped from
the screen drum immediately upon entering
the same. In order to overcome this diffi-
20 culty the guard-boards 26, mounted on
brackets 36 from the sheeting 37, are so
arranged that their lower edges are at an
angle to the path of travel of the apron,
as clearly seen in Fig. 2, the boards being
25 narrower at their upper ends, which serves
to spread the deposited material in a broad
path over the apron. The material being
spread in a thin broad layer instead of a
thick narrow line, enables the peas to sepa-
30 rate therefrom.

To prevent the peas from rolling off of
the edge of the apron and to strengthen
the apron along its edge and avoid stretch-
35 ing or frilling, a raised welt or bead is
formed along the edges. This ridge is pref-
erably formed by means of a rope 27, as
shown in Fig. 4, encased in a strip of can-
vas 28 stitched to the hemmed edge of the
40 canvas apron 14, the hem 38 of which being
turned under to form a bearing surface
engaging the run-boards 18, as shown in
Fig. 3.

Beneath the upper end of the separating
45 apron is a chaff and dirt carrier extending
lengthwise of the machine and adapted to
receive the chaff and dirt as it falls from
the apron, such carrier preferably consisting
of suitably driven conveyer chains 29 pass-
ing around sprockets 30 and connected by
50 cross-slats 31 to push the dirt and chaff
along a floor 32. A scraper 33 is hinged
to the frame of the chaff and dirt carrier
and is yieldingly held against the surface
55 of the separator apron 14 by means of a
spring 34 or weight. The scraper 33 is so
positioned above the carrier as to cause
the material to drop from the apron near
the middle of the carrier and so prevent
60 it from falling on the chains. An inclined
guard-board 35 on the other side of the
carrier frame serves the same purpose of
protecting the chains from becoming fouled
by the leaves and dirt.

The operation of and the advantages for
65 the various features of this invention have

been stated in connection with the descrip-
tion thereof. They all serve to make the
separating apron more efficient, more dura-
ble and less liable to fouling. The ridged
70 edges of the apron make it possible to use
rigid guard-boards sufficiently spaced from
the apron to avoid contact therewith and
dispense with the necessity for flexible
guards that tend to wear the apron on
75 account of the unevenness of the apron and
its flopping motion during operation.

What I claim as new and desire to secure
by Letters Patent:

1. An inclined upwardly travelling sep-
arating apron for viners and the like, means 80
for giving the apron a varying tension to
produce a vertical whipping action, the side
edges of said apron being free to respond to
such vertical whipping action, and raised
85 flexible ridges at such edges of the apron
formed only on the outer surface thereof to
prevent the whipping action on the apron
from causing the material to be thrown from
the edges.

2. An inclined upwardly travelling sep-
arating apron for viners and the like, mounted
90 to have a varying tension to give it a
vertical jerking motion, and flexible ridges
formed in the edges of the apron on the
outer surface only thereof by means of ropes
95 encased in fabric strips and stitched to the
edges of the apron.

3. An inclined upwardly travelling sep-
arating apron for viners and the like, mounted
100 to have a varying tension to pro-
duce a vertical jerking motion, and having
its edges free to partake of such motion,
flexible ridges formed on the edges of the
105 apron by a rope secured to the outer surface
of the apron, and guides on which the inner
surface of the edges of the apron may bear.

4. An inclined upwardly traveling agi-
tated separating apron for viners and the
110 like, a rope extending along the outer sur-
face of the unconfined edge of the apron,
and a strip of fabric encasing the rope and
stitched to the inwardly turned hemmed
edge of the apron.

5. In a separating apron for viners and
the like, run-boards on which the edges of
115 the apron bear, and inclined drain-boards
between the upper and lower bights of the
apron for carrying material falling from the
run-boards beyond the edge of the lower
bight of the apron.

6. In a separating apron for viners and
the like, run-boards on which the edges of
120 the apron bear, a platform beneath the
upper bight of the apron and spaced from
the run-boards to permit material to fall
through the space between them, and in-
125 clined drain-boards for conducting such
material beyond the edge of the lower bight
of the apron.

7. In an inclined upwardly traveling agi-

tated separating apron for viners and the like, an inclined rigid guard-board overhanging the edge of the apron and out of contact therewith, with its lower edge at an angle to the direction of travel of the apron to spread the material falling therefrom over the apron.

8. In an inclined upwardly traveling agitated separating apron for viners and the like, inclined rigid guard-boards overhanging the edges of the apron and out of contact therewith, with their lower edges diverging toward the upper end of the apron to spread the material falling therefrom over the surface of the apron.

9. In an inclined upwardly traveling separating apron for viners and the like mounted to have a varying tension to produce a jerking action, a chaff and dirt carrier beneath the upper end of the apron, and a yielding scraper engaging the lower bight of the apron to scrape material therefrom upon

the middle portion of the chaff and dirt carrier.

10. In an inclined upwardly traveling separating apron for viners and the like mounted to have a varying tension to produce a jerking action, a chain and slat chaff and dirt carrier beneath the upper end of the apron, a spring actuated scraper on one side of the carrier engaging the lower bight of the apron to scrape material therefrom upon the central portion of the carrier, beyond the chain on that side of the carrier and an inclined guard-board on the other side of the carrier to prevent the chaff and dirt falling on the chain on that side of the carrier.

In testimony whereof, I affix my signature, in presence of two witnesses.

FRANK HAMACHEK.
